UNITED STATES PATENT OFFICE.

CHARLES SCHOFIELD, OF PHILADELPHIA, PENNSYLVANIA.

FIBER-CLEANING MACHINE.

No. 881,445.

Specification of Letters Patent. Patented March 10, 1908.

Application filed September 3, 1907. Serial No. 391,143.

To all whom it may concern:

Be it known that I, CHARLES SCHOFIELD, a citizen of the United States, residing in Philadelphia, Pennsylvania, have invented 5 Improvements in Fiber-Cleaning Machines, of which the following is a specification.

My invention relates to that class of fiber opening and cleaning machines commonly termed "lumpers", "finishers" or "mixing 10 pickers" which are usually employed for the purpose of separating lumps or other foreign substances from straight or clean fibers.

The object of my invention is to so construct such a machine as to improve the action of a certain retainer plate or block usually employed in connection with the toothed drum of the machine. This object I attain 15 in the manner hereinafter set forth, reference being had to the accompanying drawing, in 20 which

Figure 1 is a longitudinal vertical section of sufficient of a machine of the class to which my invention relates to illustrate those portions of the machine forming the subject of 25 my invention; Fig. 2 is a perspective view of the end portions of the retainer plate or block made in accordance with my invention; Fig. 3 is a perspective view of one of the controllers for said retainer block, and Fig. 4 is a 30 sectional view illustrating a modification of my invention.

The machine to which my invention is applied comprises a toothed drum 1, carried by a shaft 2, which is adapted to bearings in 35 suitable side frames of the machine and is provided with any appropriate means for effecting its rotation, the machine also having a feed belt or apron 3, a pair of toothed feed rolls 4 and 5 rotated as indicated by the 40 arrows in Fig. 1, and a retainer plate or block 6, the latter having, at each end, a fork 7 resting upon the journal or body of the upper feed roll 5, and the inner face of this block 6 being curved to conform substantially with 45 the path followed by the ends of the teeth of the drum 1, the purpose of the block being to press upon the points of the teeth the stock fed to the drum by the feed rolls 4 and 5. Usually, however, this retainer block is 50 carried by arms pivoted to the side boards 7 of the feed table, and, when stock is being fed between the feed rolls, the rise of the upper roll imparts a lifting movement to the block and the latter therefore swings in an 55 arc having its center at the pivot pins of the

block-carrying arms, the result being that the block is swung away from the points of the drum teeth, and the stock is not properly guided to and pressed upon said teeth, with the further result that the knots, lumps, or other foreign matters are not properly separated from the clean, straight fibers. With the view of overcoming this objection I provide each end of the block 6 with a plate 9, having an outwardly projecting pin 10 for 60 engagement with a slot 11 in an arm 12 which is pivoted at 13 to one of the side plates of the machine, the latter being also provided with an opening for the passage of the pin 10, as shown in Fig. 1.

The upper or free end of the arm 12 has a segmental slot 14 for the reception of a clamping screw 15 with which the side plate of the machine is provided. When, therefore, the block 6 rises with the upper feed roll 5 upon 65 the passage of stock between the feed rolls, the upper end of the block is, because of the guiding influence of the pin 10 and slot 11, caused to move in a curved path substantially parallel with the ends of the drum teeth, consequently the performance of its proper function by said block 6 is not affected by any rising or falling movements imparted to it.

The slotted upper end of each of the guide 70 arms 12 permits of such adjustment of the latter as may be necessary in order to retain the inner face of the block in proper relation to the points of the drum teeth as said teeth become shortened through wear.

In order to properly weight the upper feed 75 roller 5 I provide a boss 16 upon the flange 17 with which each of the plates 9 is provided and which serves as a means of securing said plate upon the block 6, each of the said bosses 16 having a projecting rod 19, upon which is 80 adjustably mounted a weight 20, as shown in Fig. 2.

While I prefer to provide each end of the block 6 with guiding and retaining devices of 85 the character which I have described, it may be sufficient, in some cases, to provide such devices at one end of the block only, and instead of adapting the pin or other projection on the plate 9 to a slot in an adjustable arm 90 on the side of the machine, such pin might enter a slot on the side plate of the frame, or the plate 9 might be slotted, as shown at 11^a in Fig. 4, for the reception of a pin 10^a projecting from the side plates of the machine or 95 105 110

from a swinging and adjustable arm 12^a thereon, as also shown in said figure.

I claim:—

1. In a machine of the character described, 5 the combination of a toothed rotating drum, feed rolls, and a retainer which is adjacent to the points of the drum teeth, partakes of the rising and falling movements of the upper feed roll and is combined with means for 10 maintaining it in proper relation to the teeth of the drum during such movements.
2. In a machine of the character described, 15 the combination of a toothed rotating drum, feed rolls, a retainer which is adjacent to the points of the drum teeth and partakes of the rising and falling movements of the upper feed roll, and a slot-and-pin guide for maintaining said retainer in proper relation to the teeth of the drum during such movements.
3. In a machine of the character described, 20 the combination of a toothed rotating drum, feed rolls, a retainer which is adjacent to the points of the drum teeth and partakes of the rising and falling movements of the upper feed roll, and means adjustable from and 25 towards the teeth of the drum, for maintaining the retainer in proper relation to said teeth during its rising and falling movements.
4. In a machine of the character described, 30 the combination of a toothed rotating drum, feed rolls, a retainer which is adjacent to the points of the drum teeth and partakes of the rising and falling movements of the upper feed roll, a slot-and-pin guide for maintaining 35 said retainer in proper relation to the teeth of the drum during such movements.

and means for adjusting said guide from and towards the points of the teeth.

5. In a machine of the character described, 40 the combination of a toothed rotating drum, feed rolls, a retainer which is adjacent to the points of the drum teeth and partakes of the rising and falling movements of the upper feed roll, a projection on said retainer, and a 45 pivoted and adjustable arm having a slot for the reception of said projection.

6. In a machine of the character described, 50 the combination of a toothed rotating drum, feed rolls, a retainer which is adjacent to the points of the drum teeth, acts upon the stock fed to the teeth of the drum by said rolls, and partakes of the up and down movements of the upper feed roll, and a weight carried by 55 said retainer.

7. In a machine of the character described, 60 the combination of a toothed rotating drum, feed rolls, a retainer which is adjacent to the points of the drum teeth, acts upon the stock fed to the teeth of the drum by said rolls, and partakes of the up and down movements of the upper feed roll, a weight carried by the retainer, and means for maintaining said retainer in its proper relation to the teeth of the drum during its up and 65 down movements.

In testimony whereof, I have signed my name to this specification, in the presence of two subscribing witnesses.

CHARLES SCHOFIELD.
